FIG. 2

UNITED STATES PATENT OFFICE.

WILLIAM E. YOUNG, OF UNIONTOWN, PENNSYLVANIA.

MINING-MACHINE.

1,315,271.

Specification of Letters Patent. Patented Sept. 9, 1919.

Application filed May 3, 1919. Serial No. 294,431.

To all whom it may concern:

Be it known that I, WILLIAM E. YOUNG, a citizen of the United States, and resident of Uniontown, in the county of Fayette and State of Pennsylvania, have invented a new and useful Improvement in Mining-Machines; and I do hereby declare the following to be a full, clear, and exact description thereof.

10 My invention relates to mining machines. The object of my invention is to provide a simple and efficient form of mining machine in which the coal may be mined rapidly and expeditiously, doing away with 15 the hand-operations now commonly employed in the mining of coal with the pick and shovel.

To these ends my invention comprises the novel features hereinafter set forth and 20 claimed.

In the drawings, Figure 1 is a plan view of my improved mining machine; Fig. 2 is a side elevation; and Fig. 3 is a detail of the frame for shifting the picks.

25 Referring to the drawing, the numeral 2 designates a suitable truck mounted on wheels 3 adapted to travel on the track 4, which is laid on the floor of the mine.

Mounted forwardly of the truck 2 is the 30 frame 5, said frame being composed of the side bars 6 which have the forwardly and upwardly extending portions 7 and the downwardly extending portions 8 with the cross bars 9, 10, 11 and 12, all going to make 35 up the frame 5.

This frame 5 is pivotally mounted on the truck 2, said truck having the king-pin 13 in the central bearing 14 on the cross member 14' of the frame. This construction provides for the lateral swinging of said frame, 40 as well as for a slight vertical movement of the frame for the purpose more fully hereinafter set forth.

At the forward end of the frame 5 are 45 the casters or wheels 15 which support the forward end of the frame when the machine is in operation, said casters traveling on the floor of the mine beyond the track 4. In order to raise the front end of the frame

and lift the casters 15 from the floor of the mine, I provide the latch hooks 16 which are mounted at opposite sides of the truck 2, said latch hooks being connected by the rod 17 so as to be capable of being operated in unison. An operating rod 18 is connected to the rod 17 and said rod 18 is connected to the lever 19 whereby the latch hooks are moved into and out of engagement with the cross-bar 10. It is apparent from the above that when the latch hooks engage 60 the cross-bar 10, the forward end of the frame will be elevated so as to lift the casters from the floor of the mine when the machine is being transported on the track 4 from one part of the mine to another. 65

A suitable electrical motor 20 is mounted on the frame 5 which has the bevel-wheel 22 which meshes with the bevel-gear 23 on the stub-shaft 24. A sprocket-wheel 25 on the stub-shaft 24 is engaged by the sprocket-chain 26. This sprocket chain 26 engages a sprocket-wheel 27 on the vertical shaft 28 journaled in bearings in the members 7 and 8 at the forward end of the frame 5. 70

A gear-wheel 30 on the stub-shaft 24 75 meshes with a gear-wheel 31 on the stub-shaft 32. Stub-shaft 32 carries the sprocket-wheel 33 with which the chain 34 engages. The chain 34 also engages a sprocket wheel 35 on the vertical shaft 36 journaled in 80 bearings in the members 7 and 8 at the opposite side of the frame 5.

At the forward end of the frame 5 are the triangular shaped chain-guides 39, said guides being supported by the standards 40 85 and 40' secured to the frame 5. The vertical shafts 28 and 36 pass through the triangular chain-guides 39 and said guides have the cutter chains 41 mounted on sprocket wheels 42, 43 and 44 at the corners 90 of said guides, sprockets 44 being secured to said shafts, said cutter-chains having suitable cutters 45. These cutter-chains are driven by power transmitted from the motor through the sprocket-chains 26 and 34, and 95 said chains being arranged at different heights, cuts will be made into the wall of coal at such different heights.

Mounted on the frame 5 is the pick-frame 46, said frame having the rearwardly extending bar 47 resting on a fulcrum at 48 on the cross-bar 9. The rear end of the bar 5 47 passes through the clevis-member 49 and the pin 50 supports said bar in said clevis-member, a number of holes 51 providing for the adjustment of the bar at different heights so as to change the angle of inclination 10 of the picks as hereinafter fully set forth.

A multiple double crank-shaft 52 is journaled in bearings 53 on the frame 5, and said crank-shaft is driven by power transmitted 15 to the sprocket 54 by means of a chain 55 passing around the sprocket 56 on the shaft 57 which is driven by a suitable motor 58. The picks 59 are mounted to reciprocate in guides 60 in the frame 46, the inner ends of 20 said picks being connected to pitmen 62 of the double crank-shaft so that said picks alternate with each other in advancing and withdrawing from the coal. These picks, as shown in Figs. 1 and 3, are secured to a 25 box-like member 61 which is adapted to reciprocate in the guides 60, said member being pivotally connected to the pitman 62 as at 63, so as to allow for the throw of the crank 52.

30 A belt-conveyer 64 is provided for conveying the coal from the forward end of the machine toward the rear, said belt being mounted on rollers 65 and 66. Power for driving said belt is transmitted from the 35 motor 58, but as said conveyer-belt forms no part of my invention, it has not been deemed necessary to illustrate or describe the same in detail. The belt 63 delivers the coal onto a conveyer-belt 67, and this belt 40 carries the coal to the rear to be delivered into a mine-car. This conveyer-belt, however, forms no part of my invention, and has not been illustrated in detail.

When my improved machine is in use, the 45 truck 2 is brought up on the track 4 into position for the machine to operate on the coal, as clearly shown in Fig. 2. The frame 5 is released by the hook-latches 16 and said frame drops with the casters 15 resting on 50 the mine-floor. Power is then applied to operate the cutter-chains 41 and these cutters cut into the coal across the wall thereof making the cuts at different heights. Simultaneously with this operation of the cutter-chain 41 the picks 59 are put into operation, said picks being inclined at an angle to the wall and working alternately on the coal above the chain-cutters. The angle at which the picks operate can be changed by 55 raising or lowering the bar 47 and securing it at the height desired in the clevis 49.

By mounting the cutter chains on the triangular frames at the front end of the ma-

chine, the chains are very materially reduced in length and less power is required 65 to operate the same thereby reducing the cost of operations, and providing a more effective cutting means.

The coal, as it is mined, is deposited on the conveyer 63 and carried to the rear of 70 the machine.

The frame 5 may be shifted laterally due to the fact that said frame is pivotally mounted on the king-pin 13, and in this way the cut may be made across the entire wall 75 of coal.

What I claim is:

1. In a mining machine, the combination of a suitable frame, triangular shaped chain-guides at the forward end of said frame at 80 different heights, cutter-chains mounted in said guides, and means for driving said cutter-chains.

2. In a mining machine, the combination of a frame, a series of triangular shaped chain-guides at the forward end of said frame arranged at different heights, a vertical shaft in said frame passing through 85 said chain-guides, means for driving said shaft, sprocket-wheels mounted in said chain-guides, and cutter-chains engaging 90 sprocket-wheels.

3. In a mining machine, the combination of a frame, a series of cutter-chains carried by said frame at different heights, picks 95 above said cutter-chains, and means for reciprocating said picks.

4. In a mining machine, the combination of a frame, cutter-chains carried thereby at different heights, picks above said cutter-chains, means for changing the angle of said picks, and means for reciprocating said picks.

5. In a mining machine, the combination of a frame, cutter-chains carried thereby, 105 arranged at different heights, picks above said cutter chains, and means for reciprocating said picks, said picks alternating with each other in advancing and withdrawing from the coal.

6. In mining machines, the combination of a frame, a series of cutter-chains arranged at different heights, means for drawing said cutter-chains, a pick-frame supported by said frame above said cutter-chains, 115 said pick-frame having guides therein, picks mounted in said guides, and means for reciprocating said picks.

7. In a mining machine, the combination of a frame, a series of chain-cutters arranged at different heights, pick-frames supported by said frame above said cutter-frames, picks carried by said pick-frame, means for reciprocating said picks, a rearwardly extending bar connected to said 120 pick-frame, said bar being fulcrumed on

said first-named frame, and means for supporting the rear end of said bar at different heights.

8. In a mining machine, the combination 5 of a frame, a series of cutter-chains arranged at different heights, a pick-frame on said frame above said cutter-chains, picks mounted in said frame, a double-crank shaft mounted in said frame, connections

between said picks and said double crank 10 shaft, the cranks of said shaft being set at different angles with reference to each other.

In testimony whereof, I the said WILLIAM E. YOUNG, have hereunto set my hand.

WILLIAM E. YOUNG.
